UNITED STATES PATENT OFFICE.

FREDERICK BREDEL, OF MILWAUKEE, WISCONSIN.

RECUPERATIVE FURNACE.

No. 841,663.

Specification of Letters Patent.

Patented Jan. 22, 1907.

Application filed October 11, 1905. Serial No. 282,253.

To all whom it may concern:

Be it known that I, FREDERICK BREDEL, a citizen of the United States, residing at Milwaukee, in the county of Milwaukee and State of Wisconsin, have invented certain new and useful Improvements in Recuperative Furnaces, of which the following is a specification, reference being had to the accompanying drawings, forming a part thereof.

10 This invention relates more particularly to apparatus for heating retorts, muffles, &c., in which air is supplied to the generators or fire-boxes to produce fuel-gas for heating the retorts, &c., and a secondary supply of air is delivered to and mingled with the combustible gases which constitute a part of the products of combustion in said generators or fire-chambers.

15 The invention consists in certain novel features of construction and in the peculiar arrangement and combinations of parts as herein-after particularly described, and defined in the claims.

20 In the accompanying drawings like characters designate the same parts in the several figures.

Figure 1 is a vertical cross-section on the line 1 1, Figs. 3 and 4, through the front or firing end of a furnace embodying the invention. Fig. 2 is a vertical cross-section on the line 2 3, Fig. 3, through the recuperator end of the furnace, the left-hand side being on the line 2 2 and the right-hand side on the line 3 3, Fig. 4. Fig. 3 is a horizontal section at 25 two different levels on the line 4 5, Figs. 1 and 2, the left-hand side being on the line 4 4 and the right-hand side on the line 5 5, Fig. 4; and Fig. 4 is a vertical longitudinal section on the line 6 6, Figs. 1, 2, and 3.

30 According to the ordinary method of building recuperative furnaces one generator or fire chamber is generally employed and if two are used they are arranged on opposite sides of the bench or at opposite ends of the furnace. The usual practice is to charge the generators or fire-boxes of these furnaces every time the retorts are drawn, the retorts being located directly above the feed-doors of the generators. The generators are ordinarily charged either five or six times during a period of twenty-four hours. As the fuel in the generator burns down the gas resulting from its combustion will differ in composition, quantity, and pressure from that produced immediately after the generator is filled or charged. To compensate for this

35 variation in the composition, quantity, and pressure, the generators of fire-boxes are arranged according to the present invention side by side, one on each side of the furnace, 60 and are connected with each other in or adjacent to the gas zone or space. If now the generators are alternately filled or charged—for example, one at two o'clock and the other at four o'clock—one generator will at all 65 times be operating at a high capacity and the other at a low capacity, and the mingled gaseous products of both will be at all times of uniform composition, quantity, and pressure and an even heat will be obtained in the re- 70 tort-chamber.

40 For controlling and regulating the combustion by the secondary air-supply the recuperators—in the present instance four in number—are located at the rear ends of the generators, and by this arrangement the supply of air to different parts of the furnace can be separately regulated so as to secure the most advantageous and economical results.

45 Referring now to the drawings for specific explanation of one among various forms in which the invention may be embodied, *a a* designate the generators or fire-boxes, which are arranged side by side on opposite sides of the furnace and are connected with each other in or adjacent to the gas zone by openings *b* through the partition-wall between them. The generators are provided with grates *c c*. Flues *d d* extend horizontally from the rear ends of the generators *a* and 50 are connected in like manner with each other by openings *b* through the intervening wall.

55 The combustion or retort chamber *e*, located above the generators and extension-flues *d*, communicates therewith through 95 tapering nozzles or passages *f*.

60 The retorts *g g* are supported at the ends by the walls of the furnace and at intermediate points by bridge walls or piers in the chamber *e*. In the present case there are 100 twelve so-called "through-retorts" arranged in three vertical tiers, each tier consisting of four retorts; but the number and arrangement of the retorts may be varied, and in place of through-retorts what are known as "back-to-back" retorts may be used, without materially affecting the operation of the apparatus so far as the improvements constituting the present invention are concerned.

65 *h* and *i* designate the gas-flues of the recuperators, the flues *h* being arranged to take gas from the rear part of the bench or combus-

tion-chamber *e*, while the flues *i* take gas from the front or generator part of the bench or combustion-chamber by way of the ducts *j*, *k*, and *l*.

5 *m*, *n*, *o*, and *p* designate the secondary air-flues of the recuperators. These air-flues supply the necessary air to different parts of the bench or chamber *e* for complete combustion of the gas therein, the course of the 10 air in its passage through said flues being indicated by arrows on the several figures of the drawing. The flue *m* supplies the rear quarter of the bench, the flue *n* the next or second quarters, the flue *o* the third quarter, and the 15 flue *p* the fourth or front quarter. The upper flues *o* and *p* communicate with the combustion-chamber *e* through distributing-ducts *q* and *r*, while the upper flue *m* communicates with said chamber through the 20 duct *s*, and the upper flue *n* communicates with that part of the upper flue *m* which is next to the center of the bench or furnace, as shown in Fig. 3. The upper flue *m* may be divided at the center by a partition *t*, as 25 shown in Fig. 3; but this division is not essential, since by regulating the admission of air into the flues *m* and *n* the quantity delivered to the different parts of the combustion-chamber *e* supplied by said flues can be varied 30 as desired.

The primary air-supply is conducted to the generators below the grates *c* through flues *u*, *v*, *w*, and *x*, as shown in Figs. 1 and 3. All 35 the air-supply flues are provided with dampers or valves (not shown) for regulating the primary supply under the grate and the secondary supply to different parts of the combustion-chamber. In the furnace shown in the drawings there are four recuperators, two 40 on each side of the furnace, and eight valves or dampers for the control and regulation of the primary air-supply and eight for the secondary air-supply; but any kind of recuperators—such, for example, as that shown and 45 described in United States Letters Patent No. 659,602, issued to me October 9, 1900—with any suitable number and arrangement of flues for supplying air to the furnace, may be used.

50 The generators, combustion or retort chamber, with the retorts and the recuperators, are all mounted in and inclosed by a brick setting or other suitable walls, substantially as shown in the drawings.

55 The furnace constructed as herein shown and described operates as follows: The generators *a* are filled or charged at intervals with coke either direct from the retorts *g* by means of a charging-funnel or with cold coke 60 or other fuel. Air is admitted under the grates *c* through the flues *u*, *v*, *w*, and *x*, as indicated by arrows in Figs. 1, 3, and 4, and passing through the hot coke or other fuel in the generators first produces carbon dioxid, 65 which in contact with the incandescent fuel

is partly converted into carbon monoxid. This carbon monoxid passing freely through the openings *b* from either generator which for the time being is operating at a higher capacity mixes with the gas in the other generator, thereby equalizing the pressure in both generators, so that an even supply of gas of uniform pressure and composition is supplied to the combustion or retort chamber *e* through the nozzles or passages *f*. 70 Meeting with the air from the several flues leading into the combustion-chamber the gases are completely burned and passing upwardly and downwardly between and around the retorts *g* impart their heat thereto. The 75 waste or spent gases pass downwardly from the combustion-chamber directly into the flues *h* and through the ducts *j*, *k*, and *l* into the flues *i*, from which they escape in the lower part of the furnace into a collecting 80 flue or chimney, as indicated by arrows on the several figures of the drawings. The spent or waste gases in their passage through the flues *h* and *i* heat the air entering the furnace through the adjoining flues *m*, *n*, *o*, *p*, *u*, 85 *v*, *w*, and *x*.

Various changes other than those hereinbefore mentioned in details of construction and in the arrangement of parts of the furnace may be made without departing from 90 the principle and intended scope of the invention.

I claim—

1. In a recuperative furnace two generator or fire chambers arranged side by side, and communicating with each other through openings in the wall between them, a combustion-chamber located above and communicating with both generator or fire chambers through passages in the upper walls thereof, 100 and retorts mounted in said combustion-chamber, substantially as described.

2. In a recuperative furnace two generator-chambers having extension-flues in the gas zone arranged side by side, a combustion-chamber located above said flues, a wall between the flues and combustion-chamber which communicates with both flues through 105 passages in the intervening wall, and retorts in said combustion-chamber, substantially as described.

3. In a recuperative furnace two generator-chambers having horizontal extension-flues in the gas zone arranged side by side and communicating with each other through 110 openings in the wall between them, a combustion-chamber communicating with both of said flues through passages in the intervening walls, and retorts in said combustion-chamber, substantially as described.

4. In a recuperative furnace two generator or fire chambers arranged side by side and communicating with each other adjacent to their gas zone through openings in the wall 115 between them, a combustion-chamber com-

5 municating through openings with the generator-chambers, retorts mounted in said combustion-chamber, and recuperators having primary air-flues leading into the generator-chambers and secondary air-flues leading into the combustion-chamber, substantially as described.

10 5. In a recuperative furnace two generator or fire chambers arranged side by side, a combustion-chamber communicating with said generator-chambers, retorts mounted in said combustion-chamber, and recuperators having primary air-ducts leading into the generator-chambers, and a plurality of independent secondary air-ducts leading into different parts of the combustion-chamber, substantially as described.

15 6. In a recuperative furnace two generator or fire chambers arranged side by side and

communicating with each other through 20 openings in the wall between them, a combustion-chamber located above and communicating with said generator-chambers, retorts mounted in said combustion-chamber, and recuperators having primary air-25 flues leading into the generator-chambers, secondary air-flues leading into the combustion-chamber, and gas escape-flues leading from the combustion-chamber and adjoining the air-flues, said chambers and recuperators being inclosed together, substantially as described.

In witness whereof I hiereto affix my signature in presence of two witnesses.

FREDERICK BREDEL.
